[57] CLAIM

The ornamental design for a pollutant collector for
cleaning air rising from kerosene heater, as shown and
described.

DESCRIPTION

FIG. 1 is a perspective view of a pollutant collector for
cleaning air rising from a kerosene heater, showing my
new design;

FIG. 2 is a side elevational view thereof;

FIG. 3 is a top plan view thereof, and

FIG. 4 is a bottom view thereof.

The broken line disclosure of a kerosene heater in FIG.
1 is for illustrative purposes only and forms no part of
the claimed design.

FIG. 1.

FIG. 2.

FIG. 3.

FIG. 4.
